UNITED STATES PATENT OFFICE.

PHILIP SILVERMAN, OF NEW YORK, N. Y.

DESIGN FOR LEATHER, SKIN, FABRIC, OR ARTICLE OF SIMILAR NATURE.

Application filed January 4, 1922. Serial No. 30. Term of patent 3½ years.

To all whom it may concern:

Be it known that I, PHILIP SILVERMAN, a citizen of the United States, and a resident of the city of New York, borough of Manhattan, in the county of New York and State of New York, have invented a new, original, and ornamental Design for Leather, Skin, Fabric, or Article of Similar Nature, of which the following is a specification.

Reference is to be had to the accompanying drawings, in which—

The figure is a plan view of a piece of fabric or leather embodying the new design.

I claim:

The ornamental design for leather, skin, fabric, or article of similar nature substantially as shown.

PHILIP SILVERMAN.
